SAW SETTING DEVICE FOR EDGERS

John Heaps and John Morton Heaps, New
Westminster, British Columbia, Canada

Application March 29, 1938, Serial No. 198,706

2 Claims. (Cl. 143—37)

Our invention relates to improvements in saw setting devices for edgers, the objects of which are to provide a plurality of hand wheels for adjusting the position of the saws upon the mandrel and for locking said saws in any adjusted position. A further object is to provide means for automatically locking the hand wheels against rotation.

The invention consists essentially of a setting device having axially aligned hand wheels, each of which is operatively connected to a saw setting fork and means for locking the hand wheels against independent rotation, as will be more fully described in the following specification and shown in the accompanying drawings, in which:

Fig. 1 is a part plan view of an edger showing the invention.

Fig. 2 is a sectional view of the invention taken on the line 2—2 of Figure 1.

Fig. 3 is a front elevational view.

Fig. 4 is a detail sectional view of the hand wheel locking means and is taken on the line 4—4 of Figure 1.

In the drawings like characters of reference indicate corresponding parts in each figure.

The numeral 1 indicates generally the frame of an edger in which is journaled a saw mandrel 2 fitted with a plurality of sliding collars 3 non-rotatably connected to the mandrel, and a circular saw 4 secured to each of the collars. Mounted parallel to the mandrel 2 is a slide bar 5 upon which are slidably mounted brackets 6, each of which support a saw setting fork 7. Each of said brackets is provided with horizontally projecting arms 8 through which the bracket is moved along the slide bar.

Extending across the front of the frame is a horizontal front member 10 which forms a support for a gear housing 11 having front and rear walls respectively numbered 12 and 13. The front wall 12 of the gear housing carries a bearing 14 in which is journaled three concentric sleeves 15, 16 and 17, see Figure 4, all of which extend into the gear housing 11. The sleeves are fitted respectively with a hand wheel 18A, 18B and 18C and pinions 19A, 19B and 19C. The hand wheels are each provided with a hollow boss 20 having at its rear end a conical clutch element 21, which is adapted to coact with a complementary clutch element 22 of an adjacent boss or in the case of the wheel 18A with a complementary clutch element on the bearing 14. The outer wheel 18C is normally engaged by a cap 23 which is journaled in a standard bearing 24 and is slidably mounted therein. The cap 23 is freely

mounted on the outer end of the sleeve 17 and is normally held in contact with the boss 20 of the hand wheel 18C by a bolt 25 passing through said cap, the sleeve 17 and the rear wall 13 of the housing 11. The inner end of the bolt is threaded as at 26 and is fitted with an adjusting nut 27, with a compression spring 28 extending between the nut and the rear wall 13 to impart an endwise thrust between the cap 23 and the bearing 14 to keep the sleeves 15, 16 and 17 from turning. The bolt 25 is fitted at its inner end with a fork 29, see Figure 2, which is connected through a bell crank 30 and a connecting rod 31 to a foot lever or pedal 32 which extends to a convenient position adjacent the hand wheels 18A, 18B and 18C.

Extending transversely through the gear housing 11 are racks 33A, 33B and 33C of rectangular cross section, which racks are suitably supported at opposite sides of the frame 1 and are permitted a very slight lateral movement through the gear housing, so that they may be locked immovably together by a clamping screw 34 extending through the end wall 12 of the gear housing, which screw is provided with a hand lever 35 to enable suitable turning effort to be imparted to the clamping screw. The racks 33A, 33B and 33C are engaged respectively by the pinions 19A, 19B and 19C and to each of the racks a projecting arm 8 with its bracket 6 and saw setting fork 7 is attached. Extending across the front of the frame is the usual graduated gauge bar 36 and extending from each of the brackets 6 is a pointer 37.

In setting the machine for operation, the saws 4 are rotated to facilitate their endwise movement along the mandrel 2 and by depressing the foot lever 32 the thrust exerted by the spring 28 between the cap 23 in the bearing 24 and the bearing 14 is relieved, so that the hand wheels 18A, 18B and 18C may be turned. The rotation of any of these wheels, say for instance 18B will impart rotation to the pinion 19B and will urge the rack 33B transversely of the edger and through the bracket 6 attached to the rack 33B, 45 and its setting fork 7 will move the corresponding saw longitudinally of the mandrel 2 to whatever position is desired, the position being read upon the graduated gauge bar 36. When all the saws have been set to position, the foot lever 32 is released, relieving the endwise pressure on the bolt 25, so that the spring 28 may impart endwise pressure between the cap 23 and the bearing 14 and lock the clutch elements 21 and 22 into intimate contact, thus preventing the hand wheels 55

18A, 18B and 18C from being turned. The clamping screw 34 is turned by the hand lever 35 to lock the racks 33A, 33B and 33C together, so that vibration during running may not allow any 5 of the saws to move from their set position upon the mandrel.

What we claim as our invention is:

1. A device for spacing saws on a mandrel comprising a plurality of slideable racks adapted 10 to be mounted parallel to the mandrel, each of said racks having saw engaging means, a pinion for imparting endwise movement to each rack, a plurality of coaxially mounted hand wheels for rotating the pinions, said hand wheels 15 having hubs, said hubs and said pinions being mounted on coaxial sleeves, a bearing surrounding the sleeves, said hubs and bearing having complementary clutch members, means normally

causing holding engagement between complementary clutch members and means for disengaging said clutch members for rotation of said hand wheels, said clutch engaging and disengaging means comprising a bolt extending through the sleeves, a cap carried by the bolt for engaging one of the hubs, a spring on the bolt for compressing the hubs between the cap and the bearing and manually operable means for thrusting the bolt against the spring. 5

2. A device for spacing saws on a mandrel as claimed in claim 1, said manually operable means consisting of a bell crank bearing against the bolt to compress the spring and a foot pedal for rocking the bell crank. 10 15
